UNITED STATES PATENT OFFICE.

JOSEPH L. FISCHER, OF APPLETON, WISCONSIN.

PRIMING DEVICE.

1,026,740.

Specification of Letters Patent.

Patented May 21, 1912.

Application filed July 26, 1911. Serial No. 640,544.

To all whom it may concern:

Be it known that I, JOSEPH L. FISCHER, a citizen of the United States, residing at Appleton, in the county of Outagamie and State of Wisconsin, have invented certain new and useful Improvements in Priming Devices, of which the following is a specification.

My invention relates to improvements in priming devices for automobiles and has for its leading object the provision of an improved device by the use of which a sufficient amount of gasoline to prime the engine may be introduced into each of the cylinders of the automobile without the necessity of opening the bonnet to turn the pet-cocks of the various priming cups.

The further object of my invention is the provision of an improved device whereby a predetermined quantity of gasoline may be simultaneously admitted to the various cylinders of the engine without the necessity of manually introducing the gasoline separately into each priming cup.

Another object of the invention is the provision of an improved device whereby the cylinders of an automobile engine may be primed without any appreciable loss in the amount of compression in the cylinders and consequently which will enable the chauffeur to start the machine on spark without the necessity of dismounting to crank the engine.

Other objects and advantages of my improved priming device will be apparent by reference to the following description taken in connection with the accompanying drawings, and it will be understood that I may make any modifications in the specific structure shown and described within the scope of my claims without departing from or exceeding the spirit of my invention.

Figure 1 represents a semidiagrammatic view of my invention applied to a four cylinder automobile engine. Fig. 2 represents an enlarged side elevation of one of the priming cups and supply and exit controlling valves or cocks therefor, and Fig. 3 represents a sectional view on the line 3—3 of Fig. 1.

In the drawings, the numeral 1 designates the cylinders of the automobile which are mounted on the frame or chassis 2, while rising from the chassis 2 at the rear of the engine is the dash board 3 of the automobile. Secured at a suitable point in the

automobile, and somewhat above the top of the cylinders is a gasoline supply tank 4 having leading therefrom the feed pipe 5 for conveying the priming fluid to the various cylinders.

Each of the cylinders 1 of the engine has rising therefrom the customary nipple 6 having inserted therein and controlling the flow therethrough the pet-cock 7 having the controlling handle or lever 8 secured to the outwardly projecting end thereof. Secured to the upper end of the nipple 6 above the pet-cock 7 is a priming cup 9, as is usual in automobile construction, said priming cup being intended to receive the priming fluid to facilitate the starting of the engine.

To cause the gasoline to satisfactorily enter the various priming cups 9, I provide the pipe 5 with the projecting faucets or branches 10 controlled by the valves 11 having the operating handles or levers 12, the lower open ends of the said pipes 10 being disposed to discharge into the priming cups 9.

To prevent the gasoline from the pipes 10 from flooding the priming cups and running over the engine where there is danger of its ignition, I preferably close the priming cups with the caps 13 having upstanding annular flanges 14 receiving the ends of the pipes 10 and making an air tight joint with said pipes and with the upper edges of the priming cup. This construction provides a double advantage, in that it both prevents spilling of the gasoline and also prevents escape of pressure from the cylinders when the pet-cocks are opened.

In the use of my invention, I connect the various levers 12 by the rod 15 terminating in a handle 16 disposed on the dash-board, a pull on said handle serving to simultaneously open the various valves to allow gasoline to flow from the tank 4 into the priming cups. After this flow has occurred, I then close the valves 11 and open the pet-cocks by drawing on the handle 17 of the rod 18 which is secured to the ends of the controlling levers 8 of the pet-cocks. Inasmuch as the valves 11 are closed the compression in the cylinders cannot escape except a slight amount into the priming cups, and consequently when the gasoline from the priming cups passes into the cylinders and the pet-cocks are again closed the compression remaining in the cylinders will frequently be sufficient to enable one to start

the engine on spark without necessitating the cranking of the same.

From the foregoing description taken in connection with the accompanying drawings the construction and use of my improved automobile priming device will be readily understood, and it will be seen that I have provided an extremely satisfactory device for supplying a small quantity of gasoline to the cylinders of an automobile engine without the necessity of opening the bonnet and separately priming the various cylinders.

I claim:

15 1. The combination with an internal combustion engine, of priming cups in communication with the various cylinders, pet-cocks for controlling flow from said cups into the cylinders, means for operating the 20 various pet-cocks in unison, a supply tank, a pipe leading therefrom, branch pipes lead-

ing from said pipe to the various priming cups, valves for controlling the branch pipes and means for operating the various controlling valves simultaneously.

2. The combination with the cylinders of an internal combustion engine, of priming cups in communication with said cylinders, pet-cocks controlling the flow from the cups into the cylinders, a supply pipe, branches 30 from said pipe discharging into the cups, valves in said branches, means for operating the various pet-cocks simultaneously, and independent means for operating the various valves simultaneously.

25 In testimony whereof I affix my signature, in the presence of two witnesses.

JOSEPH L. FISCHER.
